FASTENING FOR FOUNTAIN PEN CAPS

Wallace E. La May and George W. Chance,
Minneapolis, Minn.

Application February 21, 1938, Serial No. 191,663

5 Claims. (Cl. 120—42)

Our invention relates to fountain pens and is directed to improved means for coupling the closure cap to the barrel of the pen.

Generally stated, the invention consists of the novel devices, combinations of devices, and arrangement of parts hereinafter described and defined in the claims.

Hitherto it has been the common practice to connect the caps to the barrels of fountain pens by screw-threaded engagement; and in certain of such pens there has been provided an axially movable yieldingly pressed inner cap or sleeve which, when the threaded outer cap is applied to the barrel, will enclose the pen point and be yieldingly pressed against the end of the barrel. These older forms of caps, with the threaded engagement, are slow of application and slow of removal and will frequently become unscrewed and removed, exposing the pen point to the vest or coat to which the pen is applied, with the result that ink will be dabbed on said garments and sometimes the cap will be lost.

Our invention is directed particularly to an improved form and application of bayonet joints, whereby the cap can be applied to the pen by direct axial pressure and can be detached from the pen barrel by simply slight rotary movement.

Our improvement above indicated can be and preferably is incorporated with the closure cap having the above indicated yieldingly pressed axially movable inner cap. In this last indicated combination some highly important results are obtained, all as will hereinafter more fully appear in connection with the drawing which illustrates a preferred form of the pen.

In the said drawing, wherein like characters indicate like parts throughout the several views,

Fig. 1 shows the pen partly in plan view and partly in axial section;

Fig. 2 shows the closure cap removed from the barrel, the same being chiefly in section on the same line as Fig. 1, but with some parts in full;

Fig. 3 is an axial section of the parts shown in detail in Fig. 2 looking at the same at right angles to the direction viewed in Fig. 2;

Fig. 4 is a side elevation of the barrel and pen point;

Fig. 5 is a perspective on an enlarged scale showing the pen point and a portion of the barrel to which it is applied;

Fig. 6 is an enlarged view partly in perspective and partly in section showing the closure cap removed from the barrel; and

Fig. 7 is a section taken on the line 7—7 of Fig.

1 showing a part on the same enlarged scale as in Fig. 6.

The barrel of the fountain pen is indicated by the numeral 10 and the pen point applied thereto in the customary way is indicated by the numeral 11. This barrel and pen point may be considered of the standard construction, except that the barrel 10, at its pen-carrying end, is provided with outstanding lock lugs or projections 12 that may either be formed integral with 10 the barrel or may be of metal or other material rigidly applied to the barrel. For a reason hereinafter noted, the barrel 10, at its butt end is shown as provided with a disc-like pressure plate 13 swivelled thereto by a counter-sunk screw 14 15 or the like.

The outer end of closure cap 15 here illustrated and preferably employed is provided with an inner cap or sleeve 16 that has limited axial movement therein and is yieldingly pressed by 20 a coiled spring 17 or other resilient member which, in this instance, reacts against a plug 18 screwed into the outer or closed end of the cap 15. The numeral 19 indicates a spring finger such as usually employed in connection with the 25 caps of fountain pens and which, as here illustrated, is clamped to the cap 15 by the flanged outer head of the plug 18.

The important features of the invention are involved in a novel form of bayonet joint for 30 connecting the cap 15 to the barrel. The number of these bayonet joints may be varied but in the drawing we have illustrated the use of two such bayonet joints.

For each lock lug 12 on the barrel the cap 15 35 on the interior of its enlarged bore 20 is formed with a co-operating bayonet groove that consists of a flaring lower portion 20a, a neck 20b, and a depressed or return lock pocket 20c. It is important to note, see particularly Figs. 3 40 and 6, that the flaring portion 20a of each of the two bayonet grooves extends through 180° so that the walls of the grooves are brought together in sharp points or edges 20d. Regardless of whether there are two or more of the lock lugs 45 12 and two or more of the bayonet grooves, the expanded portions of the grooves will be brought together to form edges or points. This is important for in the structure illustrated when the cap is forced endwise onto the barrel from any 50 position of rotation, the lock lugs 12 will be directed first upward through the channels 20b and then into the lock pockets or depressions 20c; and when this is accomplished and pressure on the cap is relieved, the spring pressed in inner 55

cap 16 will be tightly pressed against the adjacent end of the barrel and the lock lugs 12 will be held seated in the pockets 20c. In this way, by the simplest kind of a movement, the cap 5 can be applied and locked to the barrel so that it will not be accidentally displaced.

By reference to Fig. 6 it will be noted that the high point *x* of the upper curve of channel 20b is circumferentially offset toward pocket 20c, 10 beyond high point *y* of the lower curve of said channel. When spring-pressed inner cap 16 is engaged with the pen barrel and reacts against the same, the lugs 12 will be forced downward beyond high point *y* and into pocket 20c. When 15 pressure is relieved while pen barrel is still at the highest possible point in channel 20b, the construction of lock pockets 20c prevents the pen locks from returning back through channel 20b, thereby assuring absolute protection against pen 20 barrel becoming separated from the cap. The relation of the points marked *x* and *y* above noted is very important for the following reasons: Assuming that the cap is held against rotation and that the pen is forced axially into the cap, it 25 is evident that the engagement of the lugs 12 with the upper curve of channel 20b will cause the pen to rotate in a clockwise direction until the lugs 12 are moved in that direction beyond the point *y*, thereby causing the lugs to move in 30 the clockwise direction past the point *y* axially into the pocket 20c. Hence, when the tension on the pen is removed, the lugs 12 will be automatically dropped into the pockets 20c. This rotary movement, which automatically locks the lugs in 35 the pockets, is produced entirely by axial pressure between the cap and the pen and eliminates the necessity of a manual rotary operation in order to locate the lugs in the pockets.

To release the cap it is only necessary to turn 40 the same slightly so as to cam the lugs 12 out of the pockets 20c, thereupon the cap will be free for the passage of the lugs 12 out through the necks 20b and expanded portions 20a.

With this structure the cap can be applied to 45 the barrel simply by holding the cap between the fingers and pressing the thumb against the pressure plate or washer 13; and in this action the slight rotation of the barrel produced by the entrance of the lock lugs into the bayonet 50 joints will be freely permitted by rotation of the said pressure plate 13.

In the drawing we have illustrated a cap 55 formed with two flaring bayonet slots each extending circumferentially through 180°, making a total flare of the two slots 360°, so as to bring

the flaring walls of the two slots to sharp or wedge-like edges. This is important because it causes the lug or lugs on the barrel to be directed through the narrow channels and into locked pockets. When the caps are pressed axially onto the barrel, the rotation of the cap will be due entirely to camming action. If, for example, the cap should be formed with three flaring bayonet slots, then each slot should flare through 120°, making a total flare of 360°.

What we claim is:

1. In a fountain pen, a barrel equipped at one end with a pen point and at the same end with a projecting lock lug, and a cap recessed to fit over the pen-equipped end of said barrel, said recess being formed with a bayonet slot that flares toward the open end of the cap, in one direction, and in the other direction is contracted and formed with a circumferentially offset lock pocket to which the outer curve of said slot extends circumferentially in the direction of the pocket to a point circumferentially beyond the high point of the inner curve of said contracted neck, so that when said cap is pressed axially on to the barrel, the lug of said barrel will be moved circumferentially into said pocket.

2. The structure defined in claim 1 in further combination with a yielding pressure device mounted in said cap and adapted to be retracted by axial pressure and when released, to hold said lug in said pocket.

3. The structure defined in claim 1 in which said barrel at its opposite end has a swiveled pressure plate adapted to remain stationary in the finger pressing the same when said barrel is rotated by the camming action of the slot of said cap.

4. The structure defined in claim 1 in which said barrel at its opposite end has a swiveled pressure plate adapted to remain stationary in the finger pressing the same when said barrel is rotated by the camming action of the slot of said cap, said cap further having a retractable spring-pressed element with which the pen-equipped end of the barrel is engageable when forced into said cap.

5. The structure defined in claim 1 in which said cap is provided with a plurality of said slots, the walls of which join at sharp-edged points so that under axial pressure the lug of said barrel will be caused to move into one or the other of the said slots.
